COMBINED REFUSE RECEPTACLE AND ARTICLE CARRIER FOR AUTOMOBILES OR THE LIKE

Wiley M. Whitaker, 227 Lexington Road,
Asheboro, N.C. 27203

Filed Dec. 28, 1970, Ser. No. 26,658

Term of patent 14 years

Int. Cl. D7—05

U.S. Cl. D49—32

FIG. 1 is a perspective view of a combined refuse receptacle and article carrier for automobile or the like illustrating my new design;

FIG. 2 is a top plan view of the combined refuse receptacle and article carrier for automobile or the like of FIG. 1;

FIG. 3 is a cross-sectional view taken along line 3—3 of FIG. 2; and

FIG. 4 is a right hand side elevational view of FIG. 2.
I claim:

The ornamental design for a combined refuse receptacle and article carrier for automobiles or the like, as shown.
